UNITED STATES PATENT OFFICE.

CLARENCE E. REED, OF WICHITA, KANSAS.

ROTARY DRILL BIT OF THE FLAT-BLADE TYPE.

Application filed November 5, 1925. Serial No. 67,001.

This invention relates to rotary drill bits, and in particular the flat blade type of bit universally known in the trade as a fish tail.

6 One object of this invention is to provide a fish tail bit of the form universally now employed in the art, so as to retain all the time tried and proven advantages of the flat blade in drilling so called soft earth formations, but combine with such time proven advantages a means of replacing the worn cutting edge without the heavy waste necessitated by the present universal practice of discarding as scrap the body and threaded 10 shank portions of the usual fish tail bits.

Numerous efforts have been made to supply detachable cutting points for fish tail, and substitute forms of bits, but in every known form there is some inherent weakness culminating always in loosened parts and loss thereof in the well. These parts, always being the hardest steel that is known to the art, and of relative small shape and volume, cause expensive fishing jobs, when they can be recovered at all, and at all times endanger the entire investment in the well. In the case of present day deep wells, such investments are seldom less than \$25,000.00 and usually more, up to \$100,000.00 or over in 20 a single well.

The object of my invention is to provide such forms and combination of elements as will retain proven advantages, but secure these advantages in an assembly, the wearing parts of which may be replaced at will at small cost, and so lock the parts together that to all practical purpose such complete assembly will be as though one solid integral piece. Heretofore, efforts in a similar 30 direction have taught the use of relatively short length cutting elements, and relatively short length portions of the cutting elements penetrating the holder member, or where variations were attempted the resulting structure lacked strength and could not be made stronger because if enlarged would eliminate some other prime essential of an operable structure, as for instance enlarging the cutting element would weaken the holder, or render worthless the retaining means known or prevent circulation of fluid to the bottom, without which a rotary bit could not be safely introduced into any well.

The invention herein disclosed consists in the new combination and arrangement of elements, in part, and the construction here-

inafter described and claimed and illustrated in the drawings, in which:

Fig. 1, a flat side view of a blade (8) with tapered bearing area (7), and cylindrical anchor section (7^a).

Fig. 2, a side view of the same, showing wedge shaped bearing (9), cutting edge and shank.

Fig. 3, plan view of blade looking down on the shank.

Fig. 4 is a view of a complete tool, half the view in section.

Fig. 5 is a view at right angles to the view of Fig. 4.

Fig. 6 is a plan view looking down on the shank of Fig. 4.

Fig. 7 is a section through Fig. 1 on the line A—A.

The improved rotary drill bit comprises an upper portion consisting of a body (1) of the usual fish tail bit form, with a threaded shank for attaching to a hollow drill stem. The middle portion of the flat body is thickened by swelling out the flat sides to a short radius. The lower end of the body is finished with a tapered central socket (2) for a given depth, beyond which the bore is cylindrical (3) and of a diameter same as determined for the small end of the tapered bore. A slot (4) is formed through the body and cylindrical bore at right angles to the longitudinal axis of the bit, and parallel to the broad flat sides of the body. The ends of the slots are cylindrical and threaded. Screw threaded plugs (5) are placed in the ends of the slot and tightened against the ends of the wedges (6). These plugs act as screw jacks to cause the wedges operating through (7^b) to draw the taper shank (7) of cutting element (8) to rigid seat in the socket (2) the cylindrical part of shank (7^a) centering, but primarily serving to anchor rigidly the cutting element (8) in the body (1). The

100 stresses set up in all bits of this species tend to pull the shank of the cutter out of the holder. This invention provides a long shank with a rigid anchoring section, a large bearing portion (the tapered socket 105 (2)) to take all thrusts of loads imposed, and the wedge (6) draw-in construction holds the cutter and body together as rigidly as if integral. There are no torque or driving stresses on the shank (7) or 110 tapered socket (2). Just below the tapered portion of the shank of the cutter element

the top of the blade portion is finished to an inclined bevel or wedge shape (9) sloping upwardly and inwardly and the construction fits a correspondingly shaped groove 5 (10) in the lower end face of the body (1). The draw-in construction (5-6-7-2) of the shank clamps the wedge shaped top (9) of the blade in the groove (10) of lower end face of body (1). The overhanging walls 10 (11) of the groove (10) drive the cutter and take all the torque. All the stresses are calculated to carry into the central heavy portion of the cutter element (8) and this is well within and securely anchored within 15 the body by the bearing area of the combined grooves (10) tapered socket (2) cylindrical bore (3) and draw-in construction.

The usual passageways for fluid circulation are provided and indicated at 12. 20 Means are provided at 13 whereby cutter can be driven out when desired.

I claim:

1. In combination in a rotary deep well drilling tool of fish tail type, a main body 25 of flat fish tail form provided with a shank at its upper end for attachment to a drill stem, said flat body having an axial socket in its lower end consisting of an upper cylindrical portion, an intermediate frusto-conical thrust-sustaining portion tapering upwardly, and communicating at its upper 30 end with the lower end of the cylindrical portion, and a lower beveled wedge-shaped portion tapering upwardly into communica-

tion with the lower end of the frusto-conical portion and extending flatwise across the lower end of the body to form a terminal wedge-shaped cutter receiving groove therein, a flat tapered and beveled cutter blade in said socket and groove having a shank 35 with a cylindrical upper part, and a frusto-conical lower part all to fit the said socket and groove, and means for drawing the shank with its blade into said body to seat them rigidly in the body, the walls of said 40 groove overhanging the blade so as to take the torque.

2. Apparatus according to claim 1, in which said body has a slot formed therethrough at the said upper cylindrical portion and extending at right angles to the longitudinal axis of the tool and parallel to the broad flat sides of the body, said cutter shank having a corresponding slot adapted 50 to align with the slot in the body, the ends 55 of said body slot being cylindrical and threaded, the intermediate portion of said body slot and the shank slot having their greater dimension parallel with the tool axis, a pair of cooperating wedges in said 60 aligning slots, and screw plugs in the threaded ends of the slot adapted to act as screw jacks to cause the wedges to draw the tapered shank and cutter blade to a rigid 65 seat in the body.

In testimony whereof, I affix my signature.

CLARENCE E. REED.
